UNITED STATES PATENT OFFICE

167,318

BAROMETER SUPPORT OR SIMILAR
ARTICLECharles Hilaire Henri Rodanet, Neuilly-sur-Seine,
France, assignor to Societe Anonyme: Eta-
blissements Ed. Jaeger, Levallois-Perret, FranceApplication January 19, 1950, Serial No. 7,348
In France July 29, 1949

Term of patent 7 years

(Cl. D52—7)

To all whom it may concern:

Be it known that I, Charles Hilaire Henri Rodanet, a citizen of the French Republic residing at Neuilly-s/Seine, Seine, France, have invented a new, original, and ornamental Design for a Barometer Support or Similar Article, of which the following is a specification, reference being had to the accompanying drawings, forming part thereof.

Fig. 1 is a perspective view of a barometer support or similar article, showing my new design.

Figure 2 is a cross section on the line II—II of Figure 1.

I claim:

The ornamental design for a barometer support or similar article, as shown.

CHARLES HILAIRE HENRI RODANET.
